WALL PANEL

Maury I. Diggs, New Orleans, La., assignor to
 Higgins Industries, Inc., New Orleans, La., a
 corporation of Louisiana

Application December 17, 1945, Serial No. 635,525

9 Claims. (Cl. 72—44)

1

This invention relates to a wall panel, useful in the fabrication of buildings and like structures.

One of the objects of the invention is to provide a panel consisting of spaced parallel sheets maintained in fixed relation by intermediate bonding members, inset from the edge faces of the panel, whereby the edge faces may be left open all around so that an integral wall core may be formed by pouring concrete in the space defined within a plurality of such panels arranged contiguously.

Another object of the invention is to provide a wall panel comprising a pair of spaced parallel metallic sheets, each having fixed thereto a plurality of spaced inwardly projecting fingers, the spacing pattern for the cooperating sheets being so related that corresponding fingers of the respective sheets lie in juxtaposition, each group of juxtaposed fingers being embedded in a pillar of set cement, whereby the fingers are bonded in fixed position and the sheets thereby fixedly secured in spaced relation.

A further object of the invention is to provide a wall panel, as above described, in which the groups of juxtaposed fingers are surrounded by collars which may be cheaply made of paper or fiberboard, of uniform height, which determine the parallel spacing of the sheets, and which serve as forms into which the pillars of cement are cast about the juxtaposed fingers.

Still another object of the invention is to provide a wall panel as described, in which the bonding fingers are tack-welded to the respective sheets in flat position, and later bent up from the surface of the sheet preparatory to assembling the panel. This permits the sheet to be handled flat in further processing, as for example, to receive the frit when the outer faces of the sheets are to be porcelain enameled, and permits the sheets to be stacked flat for transportation to the place where the panel is assembled.

Other objects of the invention will appear as the following description of a preferred and practical embodiment thereof proceeds.

In the drawings which accompany and form a part of the following specification:

Figure 1 is a perspective view of a wall panel, embodying the principles of the invention, the intermediate portion being broken away, and the spacing pattern for the bonding fingers being indicated;

Figure 2 is a section taken along the line 2—2 of Figure 1, showing also part of an adjacent wall panel;

2

Figure 3 is a section taken along the line 3—3 of Figure 1, the lower part of the panel being broken away;

Figure 4 is a fragmentary plan view of the inside of one of the panel sheets, showing a finger unit in flat condition;

Figure 5 is a fragmentary sectional view of one of the panel sheets, taken diametrically through one of the finger units, showing the fingers bent up from the plane of the sheet;

Figure 6 is an exploded perspective view, partly in section, showing the cooperative relationship of the finger units of the respective panel sheets, and the spacing collar, in forming the bonding pillar;

Figure 7 is a diametrical cross-section through the bonding pillar, the cementitious filling being omitted;

Figure 8 is a top plan view of a wall portion including a corner, fabricated from contiguous wall panels;

Figure 9 is a perspective view of a clip for securing adjacent wall panels in end to end abutment;

Figure 10 is a perspective view of a corner clip. Referring now to the drawings, the wall panel 1, comprises two spaced sheets 2 and 3, of metal, congruently arranged in spaced parallel relation. The margins of the sheets are folded twice, at 30 right angles, to give the panel flat side and end faces in a width direction, and to form channel flanges 4, extending around all sides of the sheets, defining an inner peripheral channel 5. The flanges 4 face inwardly when the sheets are set up in the panel bounding an open slot 6, which extends about the entire perimeter of the panel.

Each sheet is provided on its inner face, at spaced intervals, both lengthwise and widthwise, with finger units 7. By way of example, for an 8' by 4' sheet there may be fifty finger units, uniformly spaced apart, five to a row widthwise, the spacing pattern being identical for all sheets of a size, and equidistant from opposite edges, so that regardless of how the length dimension of

45 the sheets of a pair are relatively oriented in constructing the panel, the spacing centers of the clips, for both sheets, will be in precise transverse alignment.

Figure 4 shows that the finger units 7, each 50 in the flat, consist of a sheet metal base plate in the form of a ring 8, having stamped out fingers 9, with arcuate base portions 10 emanating from corresponding sides of outwardly extending welding lugs 8a and which follow the curvature 55 of the ring, and tangentially extending end por-

tions 11, the tangential end portions extending in the same direction with respect to the circumference of the ring. The end portions each preferably terminates in an enlarged head 12.

The fingers 9 are displaced at 90° intervals, and have weakened fold lines 13, defining their bases, diametrically opposite fold lines being parallel to a diameter of the ring.

The clips 7 are positioned concentric with the spacing centers, and oriented until the fold lines 13 at the bases of opposite pairs of fingers are offset with respect to diameters of the ring parallel to the respective length and width dimensions of the sheet. This assures that when the complementary sheet is in position, the fingers of the respective sheets will be out of metallic contact, as shown in Figure 7. The finger units are then tack-welded to the sheet, as indicated at 14, the fingers 9 being left free. The finger units are arranged identically on both sheets, so that all of the fingers of all of the finger units extend in the same direction, that is, all clockwise or all counterclockwise.

The finger units 1 are left flat until the time comes to assemble the sheets into a wall panel. When in flat position they are below the level of the flanges 4, so that they create no impediment to the flat handling or stacking of the sheets. A large stock of identical sheets may be prepared at one place and shipped stacked flat to the place of assembling. Since the spacing pattern is symmetrical with respect to the opposite sides of the sheet, there is no problem in matching the ends of the sheet in setting up the panel. To fabricate the panel, all of the fingers 9 of the sheet are bent out perpendicular to the plane of the sheet along the fold lines 13, by means of pliers or a special tool. The perpendicular fingers will be in groups of four, one group for each finger unit, two of which fingers will have their width dimensioned parallel to the length edges of the sheet, while two will be parallel to the width edges.

Collars or tubes 15 are provided for each group, said collars being in the form of cylinders of uniform height, open at both ends and of a diameter to snugly embrace the fingers about their arcuate portions 9 and to enclose the arcuate ends 13a of the lugs 8a. The cylinders may be of plural ply paper, waterproofed with shellac.

One of the sheets is now laid flat with the fingers uppermost, and a collar 15 is slipped over each group of four fingers until the lower end of the collar rests upon the sheet. The collars are self-centering, since they are guided by the cam surfaces afforded by the arcuate portions 10 of the fingers. Now, a settable cement composition, which preferably has thermal insulation properties, is poured into each collar in plastic state, to fill the same and to embed the fingers. The tangential portions 11 of the fingers extend inwardly toward the axis of the group and are deeply embedded in the cement. The heads 12 assist in keying the fingers in the cement. Next, the complementary sheet with projecting fingers is inverted and brought down parallel and congruently with the first sheet, to embed the groups of fingers of the complementary sheet in the cement bodies in the corresponding collars on the first sheet. The complementary sheet is pressed down until it rests upon the collars. Since these are of uniform height, they determine uniform width of spacing between the sheets and parallelism of the front and back faces of the panel.

Since the opposite fingers of each unit, when erect, are parallel respectively to the length

and width dimensions of the sheet, and since they are offset from diameters passing through the spacing centers parallel to the respective length and width dimensions of the panel, the interleaved fingers from opposite sheets will be arranged in the bonding pillar in pairs, as shown in Figure 7, the fingers of opposite pairs lying in spaced parallel planes, the pairs being 90° displaced. This arrangement affords maximum reinforcement against shearing stresses transmitted through the sheets comprising the panel, as well as stresses tending to separate the sheet.

Weights are placed upon the top sheet sufficient to hold it in contact with all of the collars while the cement is setting. This straightens out any wind in the sheets incident to the stamping of the peripheral flanges, or warping imparted during the process of porcelain enameling, so that the faces of the panel are in true planes. When the cement in the collars has become set, the weights are removed and the panels are complete.

Figure 3 shows that when the fingers 7 are bent into erect position, the arcuate base portions 9 cause the tangential end portions 11, Figure 4, to become deflected inwardly toward the axis of the bonding pillar of cement which embeds the fingers, and since it is the tangential portions of the fingers of the respective sheets which interdigitate, these embrace and confine a portion of the cementitious mass so as to cause it to compressively resist any force tending to separate the sheets in the direction of the thickness dimension of the panel.

It is preferred to cast marginal tie wires in the panel, useful for reinforcing the poured concrete mass which intersects the joints between contiguous panels, in the wall. This is done by perforating some or all of the collars 15 in the peripheral border of the spacing pattern, as indicated at 17 in Figure 2, and inserting the legs or wire loops 18 through said perforations, so as to enter or intersect the space within said collars. The legs become embedded in the cement composition and the loops thus fixed. The bights of the loops 18 extend beyond the peripheral slot 6 of the wall panel, as shown in Figure 1, but for convenience in handling the panel, they may be temporarily bent so as to lie within the confines of the panel.

The wall panels may be variously arranged in fabricating them into a wall, one of which arrangements, for example, is shown in Figure 2, in which two panels 1 and 1a are shown, placed in endwise juxtaposition with adjacent flat faces in abutment, being temporarily secured together by the resilient clips 19, which spring over adjacent flanges 4. One of these clips is shown in perspective in Figure 9, having flared sides 20, which spread when the clip is pressed against the flanges 4, to let the flanges into the channel seats 21. The reinforcing wire loops 18 are shown extending from the respective panels, each into the peripheral channel 6 of the other panel, in lapped relation intersecting the plane of the joint 22 between the panels. Concrete is poured into the space defined within the contiguous panels and about the binding pillars forming an integral wall core. Thus the panels function as self sustaining forms for the concrete, no other forms being required. The concrete is preferably of heat insulating nature.

Figure 8 shows a wall arrangement, including a corner, formed by the panel 1b, placed at right angles to the panel 1, with adjacent inner edges

of said panels in linear abutment. These edges are temporarily held together by a corner clip 23, shown in perspective in Figure 10, having sides 24, which spread when pressed against the flanges 4 to let the bases of said flanges into the channel seats 25. The sides are then bent to embrace the ends of the flanges 4, as indicated at 26 in Figure 8. The outside of the corner is closed by an arcuate sheet 27, having longitudinal rabbets 29 terminating in flanges 30. This sheet is slidably inserted from the top between the adjacent outer corners of the panels 1 and 1b. The reinforcing wire loops 18 overlap in the corner. When the concrete is poured in, it forms a monolithic wall core extending about the corner.

In addition to providing continuity of the space within contiguous wall panels, the peripheral channel 6 which surrounds each panel affords means for adjustably positioning and retaining adjunctive devices such as the roof rafter bolster 34, shown in Figure 3. This consists of a sheet metal member having an upper convex rafter seat 32, of a width to overlie the peripheral channel 6, having longitudinal right-angled rabbets forming seats which rest upon the upper ends of the respective sheets of the wall panel and terminate in flanges 33, which press the inner sides of adjacent flanges 4 of the wall panel through inherent resiliency. These flanges are thrust down into the soft concrete within the wall panel. The top of the bolster is formed with holes 34, through which more concrete may be introduced to fill the space within the bolster and unify it with the panel when the concrete has set. The convex shape of the rafter seat permits rafters to be supported upon it at various pitch angles.

The invention contemplates making the faces of the panels with a plain metal finish or porcelain enameled, or either or both faces may be of stainless steel, plain metal bonderized for wall paper, canvased or stippled, or provided with any type of finish that may be desired.

The panel construction is adapted for floors as well as walls, and for many other uses.

While I have in the above description disclosed what I believe to be a preferred and practical embodiment of the invention, it will be understood to those skilled in the art that the details of construction and arrangement of parts are by way of example and not to be construed as limiting the scope of the invention.

What I claim as my invention is:

1. Wall panel comprising a pair of spaced sheets having bonding pillars between them at various points, said bonding pillars comprising spacing tubes of uniform length against the end of which the sheets abut, a cementitious mass within said spacing tubes, and fingers juxtaposed within said spacing tubes fixed to the respective sheets and embedded in the cementitious mass.

2. Wall panel comprising a pair of spaced metal sheets having bonding pillars between them at various points, said bonding pillars comprising spacing tubes of uniform length against the ends of which the sheets abut, a cementitious mass within said spacing tubes and metal fingers juxtaposed within said spacing tubes, fixed to the respective sheets and embedded in the cementitious mass.

3. Wall panel comprising a pair of spaced sheets of the same size and shape, each having a peripheral flange to one side, perpendicular to the plane of said sheet, the free end of said

flange being inbent to form a side flange parallel to the plane of said sheet, said sheets being positioned congruently in spaced relation to form a surrounding peripheral slot bounded by said side flanges, bonding pillars between said sheets at various points, said bonding pillars comprising spacing tubes of uniform length against the ends of which said sheets abut, each spacing tube containing a cementitious mass, and fingers juxtaposed within said spacing tubes fixed to the respective sheets and embedded in the cementitious mass.

4. Wall panel comprising a pair of spaced sheets of the same size and shape, each having a peripheral flange to one side, perpendicular to the plane of said sheet, the free end of said flange being inbent to form a side flange parallel to the plane of said sheet, said sheets being positioned congruently in spaced relation to form a surrounding peripheral slot bounded by said side flanges, bonding pillars between said sheets at various points, said bonding pillars comprising spacing tubes of uniform length against the ends of which said sheets abut, each spacing tube containing a cementitious mass, and fingers juxtaposed within said spacing tubes fixed to the respective sheets and embedded in the cementitious mass.

5. Wall panel comprising a pair of spaced rectangular sheets of the same size, each having a peripheral flange to one side perpendicular to the plane of said sheet, the free end of said flange being inbent to form a side flange parallel to the plane of said sheet, said sheets being positioned congruently in spaced relation to form a surrounding peripheral slot bounded by said side flanges, bonding pillars between said sheets at various points, said bonding pillars comprising spacing tubes of uniform length against the ends of which said sheets abut, each spacing tube containing a cementitious mass and surrounding groups of fingers fixed to the respective sheets, extending into the spacing tube from opposite ends into juxtaposition within said tube, and embedded in the cementitious mass.

6. Wall panel as claimed in claim 1, including tie wires extending at one end through perforations in certain of said spacing tubes and embedded in the cementitious mass therein, said tie wires being long enough to extend beyond the peripheral boundary of the panel.

7. Face element for a wall panel of the type formed of two of said elements spaced by cylindrical spacing tubes and united by cementitious pillars within said spacing tubes which embed fingers projecting from both face elements, said face element comprising a metal sheet having a peripheral flange surrounding one side thereof, a plurality of finger units each comprising a base plate, a plurality of fingers pliably joined thereto at their base ends, said fingers being of greater length than the depth of said flange, said base plate being welded to the flange-surrounded side of said face element at points adjacent the base ends of said fingers.

8. In a wall panel of the type described, a face element comprising a metal sheet having a peripheral flange surrounding one side thereof, a plurality of finger units, each comprising a base

plate having welding lugs extending outwardly beyond the periphery thereof at uniform circumferentially spaced intervals, said base plate being welded to the flange-surrounded side of said sheet at points in said lugs, and fingers integral with said lugs extending from a corresponding side of each in a direction away from said sheet in planes substantially perpendicular thereto, said fingers extending outwardly beyond the outermost ends of the respective adjacent lugs.

9. Wall panel comprising a pair of spaced sheets having bonding pillars between them at various points, said bonding pillars comprising spacing tubes of uniform length against the ends

of which the sheets abut, a set cementitious mass within said spacing tubes, each bonding pillar including a group of fingers from each sheet, fixed thereto, juxtaposed within a spacing tube in spaced relation with their end portions interdigitating, and embedded in the cementitious mass, said end portions being inclined from opposite directions toward the axis of said pillar whereby to confine a portion of the cementitious mass within said interdigitating end portions, subject to compressive resistance to force tending to separate said sheets in the direction of the axis of said pillar.

MAURY I. DIGGS.
